SMOKING PIPE

Ben Woodcock, Fort Benton, Mont.
(P.O. Box 387, Great Falls, Mont.)

Filed Feb. 14, 1964, Ser. No. 78,637

Term of patent 14 years

(Cl. D85—8)

FIG. 1 is a side elevational view of a smoking pipe showing my new design;

FIG. 2 is a top plan view with one of the pipe stems being omitted for convenience of illustration; and

FIG. 3 is a front elevational view thereof.

The dominant feature of the design resides in the portion shown in solid lines.

I claim:

The ornamental design for a smoking pipe, substantially as shown and described.
